UNITED STATES PATENT OFFICE.

MARION W. LEGG, OF TRENTON, MISSOURI.

GATE.

No. 870,371.

Specification of Letters Patent.

Patented Nov. 5, 1907.

Application filed June 17, 1907. Serial No. 379,467.

To all whom it may concern:

Be it known that I, MARION W. LEGG, a citizen of the United States, residing at Trenton, in the county of Grundy and State of Missouri, have invented a new 5 and useful Gate, of which the following is a specification.

This invention relates to gates and its object is to provide a simple, durable, and efficient device of this character which can be constructed at slight cost and 10 which can be readily adjusted to different distances from the ground and is also capable of adjustment to compensate for sagging and to permit the gate to swing over snow drifts and the like or to allow small live 15 stock to pass beneath the gate.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is an elevation of the gate, the same being shown by dotted lines in one of the positions to which it may be adjusted. Fig. 2 is a plan view of the gate. Fig. 3 is a detail view of the 25 slideable member of the adjusting device.

Referring to the figures by characters of reference, 1 designates a gate post having preferably three or more eyes 2 extending therefrom and designed to receive a pivot rod 3 which extends through eyes 4 30 projecting from one of the end bars 5 of the gate. This end bar is connected to a similar front bar 6 by means of a rail 7 having straps 8 fastened to the ends thereof and lapping opposite faces of the bars 5 and 6 and pivoted to them. Each of the bars 5 and 6 is provided 35 at desired intervals with eyes 9 and the corresponding eyes of the two bars are connected by parallel members 10 which may be in the form of wires, ropes, chains, or wooden or metal bars. In the drawings the same have been shown formed of wire the end portions 40 of which are looped and twisted so as to pivotally engage the eyes. Brace members 11 preferably in the form of heavy wires or ropes are secured to opposite faces of the bar 5 near the upper end thereof and extend downward and are fastened to the bottom face of 45 the rail 7 adjacent the front end thereof. These brace members have a slide 12 mounted upon them and bearing upon the bottom face of the rail 7, the slide being preferably formed of a heavy metal rod folded upon itself at the center to form a handle 13 while the end 50 portions thereof are extended laterally and hooked as

shown at 14 to slidably engage the members 11. A U-shaped latch may be pivotally connected to the bar 6 as shown at 15, said latch being designed to embrace a latch post 16 so as to hold the gate in closed position, the downward movement of the latch being 55 limited by a suitable pin 17.

It will be seen that a gate such as described can be constructed at very slight cost, and should the same sag or should it be desired to raise the latch end of the gate above the hinge end thereof it is merely necessary 60 to pull said end upward a desired distance and to move the slide 12 along the members 11 and the bottom face of the rail 7 until the brace members become taut whereupon the gate will be supported as shown by dotted lines in Fig. 1. Should it be desired to raise 65 the entire gate the pivot rod 3 can be removed and the upper eye 4 of the bar 5 placed upon the upper eye 2 on the post 1, whereupon the rod 3 can be re-inserted through the eyes and the gate will be properly supported. Not only is the gate cheap to manufacture 70 but the same is very light, durable and efficient and will be found particularly desirable in view of its ease of adjustment.

What is claimed is:

1. The combination with a gate post; of a gate hingedly connected thereto and comprising end bars, a rail interposed between the middle portions of the bars, means secured to the rail and lapping and pivotally connected to the bars for holding the rail and bars together, flexible means interposed between and pivotally connected to the bars for maintaining the bars parallel, a diagonally disposed bracing device secured at one end to the upper portion of one of the bars and at its other end to the opposite end portion of the rail, a slide movable along the lower face of the rail, means integral therewith for engaging the bracing device, and a handle depending from the slide. 75

2. A gate comprising parallel end bars, a rail interposed between and pivotally connected to the middle portions of the bars, means interposed between and pivotally connected to the bars for maintaining the bars parallel, flexible bracing means disposed diagonally upon opposite faces of the gate, said means being secured at one end to the upper portion of one of the bars and at the other end to the opposite portion of the rail, a slide movable upon the bottom face of the rail, oppositely extending hooks integral 80 with the slide and movably engaging the flexible bracing device, and a handle depending from the slide. 90

In testimony that I claim the foregoing as my own, I have hereto affixed my signature in the presence of two witnesses.

MARION W. LEGG.
